BURT S. MINOR, OF SAN PEDRO, CALIFORNIA, ASSIGNOR TO REGAN FORGE & ENGINEERING COMPANY, OF SAN PEDRO, CALIFORNIA, A CORPORATION OF CALIFORNIA.

BLOW-OUT DEVICE FOR OIL WELLS.

Application filed June 9, 1926. Serial No. 114,604.

This invention relates to a packing mechanism for "packing off" tubular oil well members within a casing head.

In oil well operations it oftentimes becomes necessary to "pack off" well casing, drill pipe, oil well tubing, and the like, when the tubular pipes become "stuck" in the well and the operators are unable to move the same upwardly or downwardly to release them. It has been the practice under such conditions to pump water, oil, or semi-fluid mud of a light consistency into the well to loosen the member. Such operations while generally satisfactory in the accomplishment of the loosening operation, are sometimes fraught with considerable danger from unexpected "blow-outs", due mainly to a dilution of the heavy mud laden water that is generally employed in drilling operations to restrain the gas and oil pressures. Further, when it is undesirable to move oil well tubing or casing that has become "frozen", especially when pumping oil, water or light mud laden water to loosen the same, the detachable packing member may be quickly introduced within the head around the tubular member to pack the same in gas tight relation thereto, and thus control unexpected blow-outs, again when the oil tube, casing, drill pipe or kelly becomes "frozen" ("stuck or sanded up") a slight vertical movement will oftentimes enable the drillers to "shake loose", especially when such operations are accompanied by a circulation of a fluid, but as heretofore noted such circulations oftentimes are accompanied by unexpected "blow-outs".

By the employment of my improved "blow-out" device oil well tubing, casing, drill stem or similar tubular members may be quickly "packed off" within the head, or the packing member may be expanded to such an extent that the members may be moved frictionally within the packing member, and thus minimize the danger of "blow-outs", a slight turn of the packing expanding member usually being sufficient to tightly pack the member to the head.

It is therefore an important object of my invention to provide a casing head packing mechanism, whereby it will be possible to op-

erate various tubular members within a well without interference therefrom, and in which the expansible packing member may be readily introduced therein when it is desired to pack the member in fluid tight engagement in the well.

Further objects and advantages will become apparent as the description proceeds, reference being had to the accompanying drawings in which:

Fig. 1 is a central vertical section of the device attached to the upper end of a string of well casing, the packing mechanism being in an unexpanded position.

Fig. 2 is a similar view showing the packing mechanism expanded to pack the tubular member mounted therein.

Fig. 3 is a top plan view showing the packing mechanism locked in the casing head.

Fig. 4 is a top plan view showing the packing mechanism in an unlocked position.

Fig. 5 is a transverse section taken on line 5-5 of Fig. 1, looking in the direction indicated by the arrows thereon.

Fig. 6 is a transverse section taken on line 6-6 of Fig. 1, looking in the direction indicated by arrows.

Fig. 7 is a central vertical section through the casing head showing the relation of the guide lugs on the locking ring to the lug seats on the casing head.

Fig. 8 is a side elevation of the detachable threaded ring member of the packing expanding mechanism.

Fig. 9 is a side elevation of the packing mechanism showing the hinge construction.

Fig. 10 is a plan view of the same.

Fig. 11 is a sectional detail of the locking ring operating and retaining means.

In an embodiment of the invention herein disclosed 10 designates a tubular casing head provided with the usual vented openings 11, 12, adapted to be secured to the upper end of a string of well casing. Above the vents is formed an annular bevelled seat 13, for the reception of the expansible packing ring construction that will be more fully described hereinafter. The upper end of the casing head around its circular edge is provided with a plurality of outwardly extending seg-

mental lugs 15, equally spaced apart adapted to be engaged by similar inwardly projecting lugs 16, formed on the circular flange 17, of a flat detachable locking ring 18. The lugs 16 pass between the lugs 15 on the casing head when the ring is secured thereon, and as the lugs 16 are disposed below the plane of the lugs 15 it will be apparent that when the ring is rotated to bring its lugs into register with the lugs on the casing that the ring will be locked against vertical movement. Formed around the inner circular edge of locking ring 18 are a plurality of segmental lugs 19 equally spaced apart designed to engage, when the ring 18 is rotated to locked position, V shaped lugs 20 formed on the periphery of an internally threaded metal ring 21 of the packing expanding mechanism, the said lugs engaging similar shaped seats 22 when the ring 20 is mounted within the head, the lugs 19 of the locking ring and the V shaped lugs 20 preventing all movement of the ring 21 when the mechanism is in assembled position.

The tubular packing mechanism preferably consists of an expandible ring construction 25, formed of an upper flat metal ring 26 and a lower metal ring 27, each formed of a pair of substantially semi-circular members 28, 29, 30, 31 respectively. The oppositely disposed faces of both rings are convexed and engage the concaved faces of a packing ring 35 formed of an expandible material, such as rubber, and consisting of two semi-circular members, as shown in Fig. 6, all the members of the packing ring are secured together by means of bolts 36 whose threaded ends engage the threaded apertures formed in the members 28, 29, of the upper metal ring 26, and as the bores of the expandible ring 35, and lower ring 27 are of greater diameters than the bolts, it will be clear that on a downward pressure on the ring construction that the expandible member will be expanded laterally. Bolt 37 passes through an aperture in one end of ring segment 31, and engages a threaded aperture in one end of ring segment 28 in order that the members of all ring section may be swung apart on the pivoted bolt 37, as shown in dotted lines in Fig. 10, to engage a tubular object, such as an oil tube 38 that may be suspended within the well and casing head.

In order to expand the packing ring into a fluid tight engagement with the casing head and the oil pipe 38 or other tubular object, a short sleeve 40 having an exteriorly threaded lower end is provided. This sleeve engages the internally threaded ring 21, its lower end engaging the upper surface of the metal ring member 26 of the expandible packing construction, whereby when the sleeve 40 is rotated downwardly by means of the handles 41 secured thereto the split expandible ring 35 will be expanded laterally into fluid tight engagement with the interior surface of the

head and the peripheral surface of the tube 38.

As heretofore noted in the "brief description" of the invention, the packing ring may be expanded to any desired degree from a slight frictional engagement with the oil tubing to an expandible packing fit. As the internal diameter of the sleeve 40 is the same as the inner diameter of the casing it will be possible to freely utilize drilling tools within the well by simply removing the split packing ring construction, this operation being accomplished by simply rotating the lugs of the locking ring 18 out of engagement with the lugs of the internally threaded ring. The ring and the sleeve 40 attached thereto may then be raised vertically and the expandible packing ring may then be easily removed from the head.

In order to facilitate rotary movements of the locking ring 18 and the threaded sleeve 40, each are provided with a pair of operating handles 41, 42, respectively. The inner ends 43 of handles 42 project beyond the inner peripheral surface of the flange 17 of the locking ring 18, and engage a pair of the lugs 15 on the casing head when the ring is rotated to an unlocked position to prevent an accidental detachment of the ring from the head when the packing ring construction is withdrawn therefrom.

The lugs 44 having inclined surfaces that are formed on the upper surface of the locking ring are designed to guide the lugs 20 on the threaded ring 21 into their seats 22 when the packing expanded mechanism is lowered into the casing head.

What I claim is:

1. In a blow out device for oil wells, a vented casing head member adapted to be detachably secured to the upper end of a well casing, a packing ring seated in the head above the vented openings, an internally threaded ring seated in the head above the packing ring, means formed on said ring for preventing a rotary movement of the same an externally threaded sleeve engaging the threaded ring and bearing against the packing ring to expand the same laterally, and a locking ring secured to the head to maintain the threaded ring against vertical movement.

2. In the blow out device for oil wells, a vented casing head member adapted to be detachably secured to the upper end of a well casing, said casing head having an internal seat directly above the vented openings, a packing ring disposed on the internal seat of the packing head, the upper internal wall of said casing head being provided with a plurality of V-shaped seats, an internally threaded ring having a plurality of V-shaped lugs on its peripheral surface adapted to engage the V-shaped seats of the packing head, whereby to prevent rotation of the threaded ring, an externally threaded sleeve engag-

ing the threaded ring and bearing against threaded ring into the V-shaped seats of the the packing ring to expand the same laterally, casing head when assembling the packing and a locking ring secured to the head to lock expanding mechanism. 10
the threaded ring against vertical movement, In witness that I claim the foregoing I have
5 the upper surface of the locking ring being hereunto subscribed my name this 10th day of provided with a plurality of inverted V- May, 1926.
